(57) **CLAIM**

The ornamental design for a sled brake shoe, as shown and described.

DESCRIPTION

FIG. 1 is a perspective view of a sled brake shoe comprising the new design;

FIG. 2 is a top plan view thereof;

FIG. 3 is a right side elevational view thereof, which is a mirror image of the left side elevational view thereof;

FIG. 4 is an end elevational view thereof, which is identical to the other end elevational view;

FIG. 5 is a bottom plan view thereof;

FIG. 6 is a perspective view of the new design mounted on a sled shown in phantom; and,

FIG. 7 is a perspective view of another embodiment comprising the new design.

In the drawings, the broken lines depict environmental subject matter only and form no part of the claimed design.
